UNITED STATES PATENT OFFICE

FRED M. McHENRY AND THOMAS S. WILKES, OF CORVALLIS, OREGON; SAID WILKES
ASSIGNOR TO SAID McHENRY

SANITARY TOILET

Application filed May 2, 1929. Serial No. 359,960.

The invention relates to improvements in toilets of the general type in which a charge of chemicals is supplied to a point below the seat each time the toilet is used.

5 One object of the invention is to provide a new and improved means for discharging the requisite amount of chemical each time the seat cover is raised.

Another aim is to provide a receiving pan 10 for the excrement and the chemical, said pan normally hanging in a discharge position within a receptacle under the seat but being automatically movable to an elevated receiving position each time the seat cover is raised.

15 The construction herein disclosed is for the purpose of handling a liquid chemical contained normally in a tank, and still further aims are to provide unique means for discharging the liquid in measured charges from 20 said tank, to prevent further discharge of liquid from the tank when said liquid has reached a predetermined low level, and to operate the liquid-discharging means from the seat cover in such a way that opening of the 25 latter is retarded when the liquid discharge means is held against functioning, thereby signifying that it is time to recharge the tank.

With the foregoing and minor objects in view, the invention resides in the novel subject matter hereinafter described and claimed, 30 description being accomplished by reference to the accompanying drawing.

Fig. 1 is a side elevation.

Fig. 2 is a front elevation.

35 Fig. 3 is a vertical sectional view on line 3—3 of Fig. 2.

Fig. 4 is an enlarged view through portions of the contrivance on line 4—4 of Fig. 2.

40 Fig. 5 is a vertical sectional view on line 5—5 of Fig. 4.

Fig. 6 is an enlarged fragmentary view similar to a portion of Fig. 4 but illustrating the manner in which the chemical elevating bucket is tilted to its discharge position.

45 Fig. 7 is a top plan view of the bucket with the upper slides thereof omitted.

The drawings above briefly described illustrate the preferred form of construction and while such construction will be herein specifically explained, it is to be understood that

within the scope of the invention as claimed, variations may be made.

In the drawings, a continuous wall 10 is shown supporting a seat 11 and projecting a suitable distance above a floor 12, and below this floor is a receptacle 13 for liquefied excrement and the liquefying and germ-killing chemical, said receptacle being provided with a discharge pipe 14 to a drainage bed or any other desired point of discharge. Immediately under the seat 11 is an appropriate hopper wall 15, and somewhat behind this wall 15, is a rock shaft 16, at least one end of which projects to the exterior of the wall 10. Secured to this shaft is a shallow imperforate chemical and excrement receiving pan 17 which is normally lowered to the discharge position seen in full lines in Fig. 3. Provision is made however for automatically raising said pan 17 to the dotted line position 60 of Fig. 3 when the seat cover 18 is raised. In the present showing, a wheel 19 is secured on one end of the shaft 16, and a link 20 connects said wheel with the cover 18 to effect upward swinging of the pan 17 when said cover 65 is raised and downward swinging of said pan when the cover is again lowered.

A tank 21 for liquid chemical is mounted behind the parts above described, said tank being provided with a chemical-conducting pipe 22 leading to a point at which it may discharge into the pan 17 when the latter is raised to receiving position. The inlet end of the pipe 22 is in the form of a funnel 23 disposed within the tank 21. A chemical elevating bucket 24 is provided for elevating a predetermined quantity of the liquid chemical and dumping it into the funnel 23 each time the pan 17 is in position to receive such chemical. At opposite sides of the bucket 24 we provide the latter with a lower slide 25 and with an upper slide 26, a pivotal connection being provided between the two lower slides and the bucket. Preferably, the lower slides 25 are in the form of eyes secured to the ends of a rod 27 which pivotally supports the bucket 24, and by preference the upper slides 26 are in the form of eyes secured to said bucket. Vertical guide rods 28 provide a track for the bucket, said guide rods 100

being secured in the tank 21 and having their upper ends 29 curved laterally to points near the upper end of the funnel 23. The slides 25-26 are engaged with the rods 28 and when the bucket 24 is elevated as seen in Fig. 6, the slides 26 travel onto the rod ends 29, thereby tilting said bucket to a discharging position, in which it dumps into the funnel 23.

10 Suspending links 30 are shown pivotally connected with the bucket, preferably by providing them with eyes 31 engaging the rod 27. The upper ends of these links are connected with the lower end of an elevating 15 chain 32 and the upper end of this chain is secured to a sprocket 33, this sprocket being secured upon a rotatably mounted horizontal shaft 34, at least one end of which extends to the exterior of the tank 21. A wheel 35 is 20 secured to the outer end of shaft 34 and a belt 36 passes around this wheel and the wheel 19 above described, both wheels being preferably grooved to prevent slipping of the belt therefrom.

25 By the construction above described, each time the seat cover 18 is raised and the pan 17 is raised to receiving position, wheel 19 and belt 36 drive wheel 35, shaft 34 and sprocket 33, causing the latter to upwardly 30 pull the chain 32, thereby raising the full bucket 24 to the dumping position shown in Fig. 6 so that its contents of chemical will be discharged into the funnel 23 and will run from the latter by gravity into the aforesaid pan 17. The excrement is thus received in this ample supply of chemical and after use 35 of the toilet when the cover 18 is again closed, the chemical and the excrement are discharged into the receptacle 13 wherein complete liquefaction takes place in the usual way. During closing of the cover 18, the shaft 34 and sprocket 33 are reversely rotated and the bucket 24 returns by gravity to its liquid-receiving position.

40 A float 37 is provided in the tank 21 and there is provision made, controlled by this float, for locking the bucket 24 against ascent when lowering of the liquid level in the tank 21 permits dropping of said float to a predetermined position, which position is shown in 45 the drawings. In the present disclosure of the invention, float 37 is carried by an arm 38 which is secured to a rock shaft 39, said arm being provided with a rigid projection 50 which overlies the bucket 24 when sufficient downward swinging of said arm is permitted by descent of the liquid level to a low plane. When bucket 24 is thus locked against ascent, 55 attempt to raise the seat cover 18 will meet 60 with resistance, and this resistance is an indication that the chemical tank should be recharged.

If desired, shaft 39 may be provided with an indicator 41 on one of its ends co-operable 65 with indicating means 42 to show at any time

the substantial amount of liquid in the tank.

In the receptacle 13 is a hinged sludge pan 43 which may be held in various positions by the chain 44 or other desired means. The pan 17 dumps into this pan 43 each time it is lowered and said pan 43 may be adjusted to contain any desired amount of sludge, or no sludge, as may be desired, according to the strength of the chemical used, the desire of the owner, etc.

75 A ventilating pipe P is provided from the wall 10, and ventilating openings P' are formed in the rear portion of the hopper 15.

Excellent results are obtainable from the general construction shown and described and such construction is therefore preferably followed as above stated. However, attention is again invited to the fact that within the scope of the invention as claimed, variations may be made.

80 We claim:

1. In a sanitary toilet having a normally closed cover, a chemical tank, means for discharging measured charges of chemical from said tank to a point below said cover, operating means for said discharging means connected with and operated by said cover, a float in said chemical tank, and means controlled by said float for preventing operation of said charge discharging means when the chemical in the tank has lowered to a predetermined extent.

90 2. In a sanitary toilet, a seat having a cover, a receptacle under said seat, an imperforate swingable receiving pan normally hanging in a discharge position in said receptacle but movable to a horizontal receiving position under said seat, a chemical tank, means for conducting a charge of chemical from the tank to the pan each time the latter is raised, means for swinging said pan, both of said means being operatively connected with said cover to effect raising of said pan to receiving position and discharge of chemical into said pan each time the cover is raised, a sludge pan hinged in said receptacle to receive the contents discharged from said receiving pan, and means for adjusting said sludge pan to hold various quantities of sludge or no sludge, as desired.

95 3. In combination, a liquid tank, means for discharging measured charges of liquid from said tank embodying a vertically movable liquid lifting bucket in the tank and a liquid conductor into which said bucket dumps when raised, a float in said tank, and means for locking said bucket against ascent when the liquid in the tank has lowered to a predetermined extent.

100 4. In combination, a liquid tank, means for discharging measured charges of liquid from said tank embodying a vertically movable liquid lifting bucket in the tank and a liquid conductor into which said bucket dumps when raised, a float in said tank, a swingable arm

carrying said float, and a rigid projection on said arm adapted to overlie and prevent ascent of said bucket when predetermined lowering of the float and arm is permitted by lowering of the liquid in the tank.

5. In combination, a liquid tank, a vertical track mounted in said tank and having a laterally turned upper end, a liquid elevating bucket slideable along said track and its 10 turned upper end, said bucket being tilted to a discharge position by said turned upper end of said track, a liquid conductor into which said bucket dumps, and means for raising said bucket.

15. In combination, a liquid tank, a vertical track mounted in said tank and having a laterally turned upper end, a liquid elevating bucket slideable along said track and tilted to a discharge position by said turned upper 20 end of said track, a liquid conductor into which said bucket dumps, an elevating chain connected with said bucket, a sprocket from which said chain depends, said sprocket being mounted in said tank, and means for turning 25 said sprocket to raise and lower the bucket.

7. In combination, a liquid tank, two parallel vertical rods secured in said tank and having their upper ends turned in one direction, two slides movable along the vertical portions 30 of said rods, a bucket between said rods having a pivotal connection with said slides, two additional slides connected with the upper portion of the bucket and adapted to move from the vertical portions of the rods onto 35 said turned upper ends of said rods to tilt the bucket to a discharge position a liquid conductor into which said bucket dumps, and means for raising said bucket.

In testimony whereof we have hereunto
40 affixed our signatures.

FRED M. MCHENRY.
THOMAS S. WILKES.
